UNITED STATES PATENT OFFICE.

CHARLES WAGNER, OF NEW YORK, N. Y., ASSIGNOR TO ALFRED VESTER SONS, INC.,
OF PROVIDENCE, RHODE ISLAND, A CORPORATION OF RHODE ISLAND.

DESIGN FOR A SCONCE FOR LIGHTING FIXTURES.

Application filed August 19, 1921. Serial No. 493,762. Term of patent 7 years.

To all whom it may concern:

Be it known that I, CHARLES WAGNER, a citizen of the United States, residing at New York, in the county of New York and State of New York, have invented a certain new, original, and ornamental Design for a Sconce for Lighting Fixtures, of which the following is a specification, reference being had to the accompanying drawing, forming part hereof.

The figure is a perspective view of a sconce for lighting fixtures, showing my new design.

I claim:

The ornamental design for a sconce for lighting fixtures, as shown.

CHARLES WAGNER.
